United States Patent Office

Des. 220,373

Patented Mar. 30, 1971

220,373

GRATER BIN OR THE LIKE

Kurt Krusche, Frankfurt, Germany, assignor to Hutzler
Manufacturing Company, Long Island City, N.Y.

Filed July 30, 1969, Ser. No. 18,475

Term of patent 14 years

Int. Cl. D7—05

U.S. Cl. D89—1

FIG. 4.

FIG. 5.

FIG. 1 is a perspective view of a grater bin or the like showing my new design;

FIG. 2 is a front elevational view;

FIG. 3 is a side elevational view;

FIG. 4 is a top plan view; and

FIG. 5 is a rear elevational view.

I claim:

The ornamental design for a grater bin or the like, substantially as shown.
